COMBINATION OIL CAN AND LIGHT

Filed Jan. 30, 1948

UNITED STATES PATENT OFFICE

2,577,857

COMBINATION OIL CAN AND LIGHT

Henry Samuel Parisotto, St. Louis, Mo., assignor
of one-half to Carman D'Amico, St. Louis, Mo.

Application January 30, 1948, Serial No. 5,338

1 Claim. (Cl. 222—113)

1

The present invention relates generally to oil can constructions, and more particularly to a novel combination oil can and flashlight in which the light is focused on the oil can spout outlet and in which there are no exteriorly disposed wires, or the like.

An object of the present invention is to provide a novel combination oil can and flashlight in which the light is focused on the oil can spout outlet, and in which the light switch is located for operation by the hand grasping the oil can handle.

Another object is to provide a novel combination oil can and flashlight in which the batteries for the light are disposed in the oil can handle and in which a portion of the wire leading to the bulb extends through a conduit provided through the chamber of the oil can.

Other objects are to provide a novel combination oil can and flashlight which is simple in construction, which is inexpensive, which is efficient in operation, which is formed to provide ready replacement of both the flashlight bulb and the batteries for powering the same, which incorporates a readily manipulatable switch, which is formed to prevent fouling of the wiring, contact points, the switch, and batteries of the flashlight portion of the combination, and which is adapted to give long service in its intended uses.

The foregoing and other objects and advantages are apparent from the following description taken with the accompanying drawing, in which:

Fig. 1 is a side elevational view of a combination oil can and flashlight formed in accordance with the teachings of the present invention;

Fig. 2 is an enlarged vertical central cross-sectional view illustrating the details of the device of Fig. 1, the top part of the spout being broken away for conservation of space;

Fig. 3 is a further enlarged fragmentary view illustrating the details of the switch;

Fig. 4 is an enlarged fragmentary vertical cross-sectional view showing details of the light bulb mount; and

Fig. 5 is a fragmentary view showing a modification.

Referring to the drawing more particularly by reference numerals, 10 indicates generally a combination oil can and flashlight incorporating the teachings of the present invention. An oil can casing 12 is shown of cylindrical form, although any desired form may be employed, which includes a chamber 14, the top of which is defined by a concave interior roof 15 which has the usual

2

centrally located threaded opening 16 which threadedly receives the base 17 of a spout 18. Associated with the spout 18 is a conventional pump mechanism 20 including a conventional reciprocating pump 21 and an operating member 22 pivotally mounted on the spout base 17 at 23 and connected to the pump 21 by a link 24.

The casing 12 includes a false top 27 spaced from the concave roof 15. A handle construction 30 is provided and includes an arcuate portion 31 preferably of insulating material, such as rubber, Bakelite, or the like, although it may be metal one end of which is secured against the casing 12 by suitable brackets 32 between the false top 27 and the roof 15. To the other end of the arcuate portion 31 is threaded a tube or casing 33, the other end of which is closed by a threaded cap 34. The arcuate portion 31 has a channel 36 therethrough closed at one end by a web 37 which supports a terminal rivet 38, to the interior portion of which is connected one end of a wire 40. The other end of the wire 40 is connected to a terminal rivet 41 supported inside the arcuate portion 31, as shown. Adjacent the terminal rivet 41 is a second terminal rivet 42 to which is connected one end of a wire 43. A conducting member 45 is mounted in the arcuate portion 31 adjacent the heads of the terminal rivets 41 and 42, and is biased by a spring 46 out of engagement therewith. A button 47 of Bakelite, rubber, or the like, is threadedly mounted on the member 45 for movement thereof into engagement with the terminal rivets 41 and 42. Manifestly, any other form of desired switch may be provided. Flashlight dry cell batteries 50 are disposed in the tube 33 and are influenced into engagement with each other and with the head of the terminal rivet 38 by the usual spring 51.

A conduit 54 is disposed in the chamber 14 of the casing 12 and opens through the roof 15, as shown, being sealed at its termini. The conduit 54 receives the wire 43.

Diametrically opposite the handle 30 a sump 56 is formed in the top 27 centrally of which is mounted a bulb socket 57. A terminal rivet 59 is mounted in the base of the socket 57 to which is connected the other end of the wire 43. A light bulb 60 is mounted in the socket 57 and engages the head of the terminal rivet 59. Preferably, the bulb 60 is of the internal reflector type to insure focusing on the end of the spout 18.

It is manifest that the casing 12 may be formed without the false top 27 and that the bulb 60 may be mounted either in a base formed substantially as shown in Fig. 2, or may extend into a protected

sheath disposed in the chamber 14. When a standard type of casing 12 is employed, the handle 30 will be modified accordingly for engagement with the roof 15 or the wall of the casing 12, in which case the conduit 54 may extend through the annular wall of the casing 12 at the handle terminus. However, these are mere modified details of construction.

In Fig. 5, the wire 43 is shown passing around the opening 16 and disposed in the space between the roof 15 and false top 27.

In use, it is manifest that one grasping the handle 30 by the tube 33 may readily manipulate the button 47 of the flashlight switch with the side of the index finger, while at the same time manipulating the operating member 22 of the pump mechanism 20 with the thumb in the usual manner. The light from the light bulb 60 will be focused on the end of the spout 18 to illuminate the oiling point. The present construction facilitates oiling and insures the oil reaching the intended places. Furthermore, the light serves as a protection against injury of the hands of the user, since, with the present device, it is unnecessary to feel one's way in the oiling operation. Machinery in operation may be readily oiled with the present device without fear of injury to the user.

It is manifest that the flashlight elements are protected against oil from within the casing 12. Furthermore, it is clear that both the bulb 60 and batteries 50 may be readily replaced.

Obviously, there has been provided a construction which fulfills the objects and advantages sought therefor.

It is to be understood that the foregoing description and the accompanying drawing have been given by way of illustration and example. It is also to be understood that changes in form of the elements, rearrangement of parts, and sub-

stitution of equivalent elements, which will be obvious to those skilled in the art, are contemplated as within the scope of the present invention which is limited only by the claim which follows.

What is claimed is:

In combination, an oil can including a casing and a spout, said casing having an interior chamber roof and a false top spaced upwardly therefrom, said chamber roof and false top being disposed circumferentially about the base of the spout and including an outer annular wall forming a vertical extension of the sides of the casing, a sump in said false top, a light bulb mounted in said sump in said false top and focused on the free end of said spout, a handle secured to said casing extension, flashlight batteries disposed in said handle, power transmitting means connecting said bulb and said batteries including a wire extending through the space between said false top and interior roof, and a switch mounted in said handle and disposed in connection with said power transmitting means for completing and interrupting the battery-bulb circuit, said switch being located for ready manipulation by the index finger of a hand grasping the handle.

HENRY SAMUEL PARISOTTO.
